UNITED STATES PATENT OFFICE.

BURTON J. DOWNING, OF ANTELOPE SPRINGS, COLORADO.

CAR-COUPING.

SPECIFICATION forming part of Letters Patent No. 535,240, dated March 5, 1895.

Application filed December 14, 1894. Serial No. 531,815. (No model.)

To all whom it may concern:

Be it known that I, BURTON J. DOWNING, a citizen of the United States, and a resident of Antelope Springs, in the county of Mineral and State of Colorado, have invented certain new and useful Improvements in Automatic Car-Couplings; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of a side elevation of the invention applied. Fig. 2 is a section on line α — α , Fig. 3, showing the link of opposing drawhead in engagement. Fig. 3 is a front view of invention applied.

This invention has relation to certain new and useful improvements in car couplings, the object being to provide a simple, strong and efficient coupling automatic in its action, the coupling being effected by impact, and capable of being uncoupled from the top or side of the car; and the invention consists in the novel construction and combination of parts, all as hereinafter described and pointed out in the appended claims.

Referring to the accompanying drawings, the letter A designates the draw-head of the coupling, having therein a link-receiving chamber B intersected by the pin-aperture a. In the bottom of said draw-head is an elongated groove or recess b, extending nearly the full length of the draw-head, and to the front end thereof, in a direction parallel with the longitudinal axis of said head. Pivoted in the rear end portion of said groove, on a pin c, is a swinging link C, adapted to be swung upward into horizontal or coupling position, by means of the angular arm d, of the rock-rod or lever D., upon a depression d' of which arm said link rests when in its down or uncoupled position. The rod or lever D is bent loosely around a projecting end of the pin c, and thence extends laterally to the side of the car having a loop-bearing at e, and terminating in a crank arm E. Loosely connected to said crank arm is a vertical rod F, which extends to the top of the car through suitable guides,

and provides means for the elevation of the link from the top of the car.

Seated in a cavity or chamber of the draw-bar, and arranged to be partially projected into the chamber B of the head, by a spring F, is a slidable bar G. Said bar, when at the limit of the forward projection forms a support for the coupling pin H, when the latter is in its raised, or uncoupled position.

Attached to the head of the pin H, is a vertically slidable bar I, whose upper end portion is bent at substantially right angles to make the connection with the pin, and whose lower portion is similarly bent, but in the opposite direction, as indicated at h, this arm h being arranged to be engaged by the arm d, before described, when the said arm is raised, thereby raising the bar I and the pin H.

The guide for the bar I consists of a groove formed in the lateral face of the draw-head, said groove being open except for the guide flanges at the edges. By this arrangement the bar and pin can be easily detached in case either becomes broken, and the bars may be bent at the shops, and carried as train supplies for application when needed.

The coupling is effected in the following manner:—The swinging link on one of the cars is raised to coupling position by the means described, that of the other car remaining idle. As the cars come together, the link enters the chamber B of the opposing draw-head, and striking the bar G, forces the latter back, and the pin falls through the link.

To uncouple, the rock-rod or lever D is operated, raising the arm d into contact with the arm h of the bar I, raising said bar and thereby the pin. The bar G then comes forward and catches the pin in its raised position.

Having thus described my invention, what I claim as new, and desire to secure by Letters Patent, is—

1. In a car coupling, the combination with the draw-head, of a slidable spring-actuated, pin-supporting bar, arranged to project into the link-receiving chamber of said head, a vertically swinging link pivoted to the under side of said head, a rock-rod or lever having an angular arm upon which said link rests when in uncoupled position, a coupling pin, and a bar slidable in a vertical guide on the draw-head, said bar being connected with said

pin and arranged to be engaged by said angular arm of the rock-rod or lever, substantially as specified.

2. In a car coupling, the combination with
5 a draw-head, having a groove in its lower face,
of a vertically swinging coupling link pivoted in the rear portion of said groove, a slide-
able, spring-actuated pin support, a coupling
pin, a pin-raising bar slideable in a way or
10 groove on the lateral face of the draw-head,
and having a bent upper portion connected to
the coupling pin, and an oppositely bent arm
at its lower portion, a rock-rod or lever having
an angular arm designed to form a support for
15 the swinging link and to engage the lower
arm of the pin-raising bar, and means whereby
said rod or lever may be operated either from
the top or side of the car, substantially as
specified.
- 20 3. In a car coupling, a draw-head A having

therein a link-receiving chamber B, an intersecting pin aperture *a*, and in its bottom a groove or recess *b* extending nearly the full length of the draw-head and to the front end thereof, a link C pivoted in the rear portion 25 of the groove, the rock-rod or lever D having an angular arm *d* adapted to swing said link into coupling position, said rod or lever being bent loosely around a projecting end of the pivot pin of said link, and thence extended 30 laterally to form an operating arm, the slide-
able bar F seated in a cavity or chamber of
the draw-bar and the spring F, substantially
as specified.

In testimony whereof I affix my signature 35
in presence of two witnesses.

BURTON J. DOWNING.
